UNITED STATES PATENT OFFICE.

JOHN J. HEYS, OF LYNN, MASSACHUSETTS, ASSIGNOR, BY DIRECT AND MESNE ASSIGNMENTS, TO THE MCKAY SHOE MACHINERY COMPANY, OF PORTLAND, MAINE.

HEEL-BREASTING MACHINE.

SPECIFICATION forming part of Letters Patent No. 636,990, dated November 14, 1899.

Application filed March 30, 1898. Serial No. 675,738. (No model.)

To all whom it may concern:

Be it known that I, JOHN J. HEYS, of Lynn, in the county of Essex and State of Massachusetts, have invented certain new and useful 5 Improvements in Heel-Breasting Machines, of which the following is a specification.

This invention has relation to machines for cutting away the heels of boots and shoes, but has relation more particularly to machines for breeding or cutting away the breasts of the heels; and it consists of a machine possessing certain features of construction and relative arrangement of parts, all as illustrated upon the drawings and now to be 10 described in detail and finally pointed out with particularity in the claims.

Reference is to be had to the accompanying drawings, and to the letters and figures marked thereon, forming a part of this specification, 15 the same letters and figures designating the same parts or features, as the case may be, wherever they occur.

Of the drawings, Figure 1 represents in plan view a machine embodying the invention. 20 Fig. 2 represents a side elevation of the same. Fig. 3 represents a longitudinal section through the same with the knife withdrawn. Fig. 4 represents a similar longitudinal section, the parts being broken away, the knife 25 in this case being at the end of its throw. Fig. 5 represents a transverse section on the line 5 5 of Fig. 2, looking in the direction of the arrow *x*. Fig. 6 represents a section on the line 6 6 of Fig. 2, looking in the direction 30 of the arrow *y*. Fig. 7 illustrates the gage with a shoe against it, so as to show the manner of centering the shoe. Fig. 8 represents the two-part gage which may be employed. Fig. 9 represents a plan view of the latter. 35 Fig. 10 represents an enlarged transverse section on the line 10 10 of Fig. 2. Fig. 11 represents a horizontal section on the line 11 11 of Fig. 5. Figs. 12 and 13 represent the knife-carrier in different positions. Fig. 14 40 shows in detail the hand-wheel and the means operated thereby for jacking the shoe prior to the cutting operation. Fig. 15 represents partially in section the knife-carrier and the gage for the knife. Fig. 16 represents a sectional view representing the same, the gage 45

being in this case omitted. Fig. 17 shows, in addition to the parts illustrated in Fig. 15, the mechanism for separating the gages for the heel. Fig. 18 represents a side elevation of the machine from the opposite side from 55 that seen in Fig. 2. Fig. 19 represents in side elevation the rear end of another embodiment of the invention. Figs. 20 and 21 are sections on the lines 20 20 and 21 21 of Fig. 19. 60

Referring to the drawings, which show one form of machine which I have selected for the purpose of illustrating the invention, *a* indicates a base-plate, which may be supported by legs or standards *a'*. Bearing-brackets *a*² rise from one end of the plate or bed, and shafts *b* *b'* are journaled therein, the former being the driving-shaft, to which power is initially applied, and the latter, *b'*, being the shaft which imparts movement to the 70 knife and which is driven at a relatively low rate of speed. Upon the shaft *b* is loosely secured a belt-wheel *b*⁴, there being suitable clutching devices between the wheel and the shaft to connect the two together whenever 75 desired. A pinion *b*² on the shaft *b* intermeshes with and drives a large gear-wheel *b*³ on the shaft *b'*, there being on the last-mentioned shaft an eccentric *c*, and connected to the strap *c'* is an eccentric-rod *c*², by means 80 of which the knife is reciprocated, as will be hereinafter described.

Upon the standard *d*, rising from the central part of the bed *a*, is a horizontal table or plate *d'*, having undercut flanges *d*², as shown 85 in Fig. 6, to receive a dovetailed carrier or slide *e*. This carrier or slide is provided with a socket *e*², as shown in Fig. 16, to receive the shank of the knife *f*. A screw *f'* is threaded into the end of the shank and bears against 90 the rear wall of the socket *e*², so that by turning this screw the knife *f* may be adjusted in and out of the socket. After being once adjusted to the proper point the knife is held against movement by a screw *e*³, passed 95 through an arch *e*⁴ of the slide and bearing against a wearing-block *e*⁵, placed upon the top of the knife. The rear end of the slide *e* is bifurcated to receive a link *g*, hinged thereto by a pintle *g'*, extending through the slide, 100

as illustrated in Fig. 16, and the link g is in turn bifurcated and connected to the eccentric-rod c^2 by a pintle g^2 . Thus far it will be seen that for each reciprocation of the eccentric-rod the slide and knife will be likewise reciprocated.

Secured to one side of the table d' is a grooved strip or plate h , slotted, as at h' , to receive the screws h^2 , which hold it in place, so but which permit it to slide back and forth relatively to the table. On its rear end the plate or strip is formed with an upwardly-projecting portion h^3 , having a curved groove h^4 , slightly offset at h^5 . (See Figs. 12 and 13.)

- 15 The groove is on the inner side of the plate, and it receives a trundle or roll g^3 on the end of the pintle g^2 , which, as stated, connects the eccentric-rod c^2 with the link g . A spring i connects a pin h^6 , projecting down from the plate h , with a pin i' , projecting out from the bracket d , so that the trundle g^3 normally remains in the offset h^5 in the slot h^4 . When the eccentric-rod is projected, the eccentric-rod and the link are in alinement or at a dead-center, and they force the knife-slide and the strip h forward until the strip h is prevented from moving farther or meets with a serious resistance, whereupon the continued movement of the eccentric-rod causes the trundle g^3 to engage the wall of the slot h^4 at h^5 and roll up the curved slot h^4 and complete its full stroke, even though the knife-slide and the strip h remain stationary. The parts c^2 and g constitute a toggle for operating the 35 knife-carrier positively or unyieldingly, and said toggle is broken by the bunter at the moment the knife has completed its work upon the heel.

Upon the strip h is mounted a finger j , shaped 40 as shown in Figs. 1 and 11 and having its free end very slightly in advance of the edge of the knife. The other end of the finger is pivoted at j' to the end of the strip h , and the free end may be adjusted relatively to the 45 knife-edge by a screw j^2 , passed through a bracket j^3 , secured to the side of the strip h , the end of said screw bearing against the finger, as shown in Fig. 17. The finger and the strip h constitute a "bunter" or mechanism 50 for stopping the travel of the knife when it has cut through the leather of the heel to a proper extent and while the power devices complete their full throw, and they likewise perform the function of destroying the operative relation existing between the eccentric-rod and the knife-carrier.

The support for the sole of the shoe consists 55 of a plate k , pivoted at k' to an arm k^2 , extending up from the bed or plate a , and in order to hold the supporting-plate k at any angle relative to the bed it is provided with a downwardly-projecting web k^3 , to which is pivoted a link k^4 , the end of which is slotted and serrated, as shown in Figs. 1 and 2. A 65 screw k^4 is passed through the slot into the bed-plate, and its head presses a serrated

washer k^5 against the end of the link, so as to hold it against movement. By loosening the screw k^4 the shoe-supporting plate may be adjusted about the pivot or fulcrum k' to the 70 angle desired. The upper converging end of the plate k is flanged, as at k^6 , to provide a support for the base k^7 of a gage k^8 for the toe of the shoe, by means of which the shoe may be properly positioned upon the plate. 75

Pivoted upon the front face of the plate are two positioning fingers or levers l , having their lower ends shouldered and outwardly spreading, as at l' . They are provided with inwardly-projecting portions l^2 , having teeth 80 upon their ends which intermesh, whereby when one of the arms l is swung about its center of motion the other arm is likewise moved and to the same extent. One of the arms l swings loosely about its pivot-stud l^3 , while 85 the other arm is rigidly secured to its stud l^4 , so that in case the latter be partially rotated or rocked the two arms will be both swung about their centers. The studs l^3 l^4 pass through slots k^9 in the plate k and are set 90 into a cross-bar m , which has a rib m' lying in a slot k^{10} in the plate k and movable longitudinally of the said plate.

Upon the upper ends of the arms l are journaled rollers l^8 , lying in a curved slot n' 95 in a guide likewise formed with a rib to project into the slot k^{10} from the front. (Shown in Fig. 3.) An adjusting-screw n^2 is threaded into the guide and has its lower non-threaded end supported in a stud k^{12} , projecting forward from the plate k and bridging the slot k^{10} , as illustrated in Figs. 3 and 4. By rotating the screw n^2 the guide-strip, together 100 with the positioning-arms l and the cross-bar m , may be all adjusted longitudinally of the plate to change the position of the arms l for shoes of different sizes or having heels of different sizes.

Usually after the heel has been placed upon a shoe in the process of manufacture a top 110 lift is spanked in place, the top lift being usually smaller than the heel, the dimensions of which are subsequently reduced by proper tools to correspond with those of the top lift. Consequently when it is desired to breast the 115 heel the shoe is positioned with relation to the top lift and not to the remainder of the heel. Hence the shoe is placed against the supporting-plate k with the corners of the heel fitting in the notches in the ends of the 120 arms l , and the toe of the shoe is held against the gage k^8 , so that the median lines of the shoe are parallel with the said gage, after which the knife is advanced to cut the heel.

The shoe is jacked against the plate by the 125 following devices: The bed-plate a is extended at a^6 to receive a bracket a^7 , on the bifurcated end of which is journaled a shaft o . The bracket is secured in place by a screw s , passed through an enlarged aperture in the bed, and 130 the bed and bracket are both serrated, so that the latter can be adjusted toward and from the

shoe-support. A hand-wheel o' is placed upon the end of the shaft, and between the bifurcated arms of the bracket a is placed a spiral cam o^3 , having its cam-rib o^4 extending between a pin o^5 , secured to a sliding bar o^6 , and a roller o^7 , as shown in Fig. 3, this roller lying in a socket in the end of the slide-bar o^6 . To the opposite end of the slide-bar is pivoted a foot-piece o^8 to bear against the top of the last 5 and press the shoe against the supporting-plate k . Thus it will be seen that by turning the hand-wheel o' the slide-bar o^6 may be forced forward or retracted as desired to clamp the shoe against the supporting-plate 10 or else release it therefrom. When the shoe has been jacked in place by the jacking device just described, the knife is advanced; but inasmuch as the positioning-arms l are 15 then in the way of the knife I provide means 20 for swinging them out of its path as it advances. These means consist of a bent arm p , secured rigidly to the pivot-stud, and a cam-lever p' , pivoted at p^2 to the table. Upon the knife-slide is mounted a roller p^3 , which 25 as the slide advances engages the bent portion of the lever p' and swings the forward end outward. The bent arm p bears against a screw p^4 , passed through the forward end of the arm p' , so that as the forward end of the latter is 30 thrust outwardly the arm p is swung about its center of motion to rock the stud and cause the lower ends of the arms l to swing apart. The arms l are connected by a spring, which 35 normally holds their lower ends together; but they are held apart by a screw q , passed through the arm p and bearing against the edge of the plate k , and by rotating the screw their ends may be adjusted toward and from 40 each other.

40 The operation of the machine is as follows: The shoe is placed against the plate k with the corners of the top lift fitting in the notches in the arms l and with the toe properly positioned with respect to the gage k^5 . Then the hand-wheel o' is rotated to advance the slide-bar o^6 to jack the shoe in place. Then by a suitable treadle mechanism (not shown) the clutch devices are thrown into operation to connect the belt-wheel b' with the shaft b . Immediately 45 thereupon through the medium of the gearing previously described a rotation is imparted to the shaft b' , and as the shaft begins to rotate the eccentric-rod is projected, forcing forward the knife-slide, which as it advances causes 50 the positioning-arms to separate and move out of the path of the knife. At this time the link and the eccentric-rod are in alinement and the knife continues its travel (the finger j and knife f passing through an aperture in plate 55 k) until the finger j strikes against the insole and stops the travel of the sliding strip h , whereupon the roll g^3 engages the curved wall h^8 of the slot h^4 and travels up the slot h^4 , while the knife and its carrier remain stationary. Then the knife slide or carrier is 60 withdrawn, and when the shaft b' has com-

pleted one revolution by devices not shown the clutch devices are thrown out of engagement with the shaft and wheel and the shaft b' is stopped.

I may employ any desired stopping device, such as a brake-shoe r , to engage a friction-disk r' on the shaft b' , the brake-shoe being connected to the sliding sleeve r^2 , which actuates the finger r^3 , through the medium of 75 which the clutch devices are actuated to engage the belt-wheel b' with the shaft b .

Where broad-toed shoes are being breasted, I may employ a gage k^5 , as shown in Figs. 8 and 9, which may be placed upon the gage k^8 and secured at any desired height thereon. The device shown is provided with two fingers k^{14} k^{14} , by means of which the corners of the toe may be positioned.

It will be observed that the edge of the knife 85 when viewed from the end is curved in the arc of a circle, and consequently it is desired that the ends of the arms l should move through the same arc, so that the shoulders on the ends of the arms may always remain in 90 alinement with the knife-edge.

By reason of pivoting the arms l they naturally move in different paths, and consequently the upper ends of the arms are provided with rollers extending into the curved 95 slot in the cross-guide n . This slot is either straight or so curved that when the arms are swung outwardly to accommodate a heel of any size the arms not only swing about their pivot-studs, but are also raised bodily, whereby they swing in an arc or in a straight line parallel with the edge of the knife, which may be either curved or straight. This is an important feature of the invention, because if the ends of the arms do not swing in an arc 105 parallel to the arc of the knife a large heel would be presented to the knife in such way that more of it would be cut away than would be desirable, while a small portion of a smaller heel would be removed, leaving the heels relatively unfinished.

Another important feature of the invention is the mechanism by means of which the knife is positively driven to cut away the heel and is automatically stopped before it has an 115 opportunity to cut the sole, this mechanism operating perfectly with heels of different thicknesses.

Heretofore breasting-machines have been of either of two kinds—that is to say, the 120 knife was positively driven a predetermined distance each stroke, and it was necessary to adjust the shoe-holder for each height of heel in order that the knife should cut therefrom the proper amount of stock or else the knife 125 was connected with its driver by yielding means, as a spring, and a bunter was positively or rigidly connected to the knife to strike against the sole and arrest the motion of the knife after it had penetrated the heel 130 to the desired extent. The present machine, however, is provided with means for posi-

tively—*i. e.*, unyieldingly—driving the knife, and also with mechanism for automatically arresting the motion of the knife when it has completed its cut through the heel and before it has a chance to cut the sole, and in this connection I desire to state that whenever I use the word “positively” in connection with the driving mechanism it will be understood that I mean thereby that the knife is driven unyieldingly.

As will be readily apparent to those skilled in the art to which this invention appertains, various changes in the construction and arrangement of the parts of the hereinabove-described machine may be made without departing from the spirit and scope of the invention, and the several features or parts may be utilized separately or in connection with machines of other constructions. For instance, in Figs. 19, 20, and 21 I have illustrated the rear end of a machine in which the throw or movement of the knife-carrier is always the same and the shoe is adjusted toward or from the knife. In this embodiment of the invention the knife-carrier is constructed substantially as hereinbefore described; but it is connected by a pivot to the reciprocating rod, so that its movements are always of the same length or degree. A carriage t is slidably mounted on the base-plate of the machine and is provided with a rigid block t' , depending into a longitudinal slot t'' , from which block a pin t''' projects downwardly and pivotally supports a block. (Shown in dotted lines in Fig. 20.) An arm u is pivoted upon a stud under the base-plate and is provided with an eccentric slot u' , into which the block t'' extends, so that if the arm be swung to one side or the other the carriage will be moved toward or from the knife-carrier. To accomplish this movement of the arm u , it is connected by a link u^2 with an arm u^3 , frictionally engaging a shaft u^4 , journaled in the end standards of the machine, and another arm u^5 , rigidly secured to said shaft, having its outer end connected by a link u^6 with a treadle, (not shown,) by means of which the belt-wheel is clutched to the main driving-shaft of the machine. A spring (likewise not shown) normally holds the arm u in the position illustrated in Fig. 20, so that the carriage is withdrawn. Upon the carriage is mounted the sliding bar o^6 , the cam o^7 , and the hand-wheel o' , the latter not being shown, and also the gage-plate, support, or abutment v for engaging the face of the heel and holding the heel in any desired plane relatively to the knife. The plate is pivoted by a pintle v' in a lug v^2 , extending upward from the carriage, and it has a downwardly-projecting finger v^3 , to which is pivoted a connecting-rod v^4 , having in its free end a slot v^5 , through which a bolt v^6 passes into the carriage to adjustably secure it. By loosening the bolt v^6 the gage-plate may be adjusted to any desired position, substantially as hereinbefore set forth. In order to pre-

vent the knife from cutting the sole when the shoe is jacked against the plate v in the carriage and the carriage is moved toward the knife, I employ a guard or bunter consisting of an arched rod w , spanning the carriage and pivoted in brackets w' , secured upon the base-plate on either side of the carriage. This rod has a finger w^2 , through which an adjusting-screw w^3 passes and bears against the base-plate, whereby the said bunter may be adjusted in lines substantially parallel with the lines of movement of the knife. In this embodiment of the invention the shoe is jacked in the carriage, and the latter is moved forward until the sole rests against the bunter. This is accomplished by the first movement of the treadle when it is depressed, the arm w^3 being frictionally mounted upon the shaft w^4 to permit a further rotation of the shaft caused by the further depression of the treadle to start the machine.

The bunter is automatically adjusted for the various heights of heels to be breasted, and in this way the cutting of the sole is prevented.

I have also contemplated the employment of a stationary knife and the use of a carriage to move the shoe against it, this being likewise included in the invention.

Having thus explained the nature of the invention and described a way of constructing and using the same, though without attempting to set forth all of the forms in which it may be made or all of the modes of its use, I declare that what I claim is—

1. A heel-breasting machine comprising a shoe-support, a knife, mechanism for forcing the knife positively or unyieldingly through the heel to the sole, and mechanism for automatically checking the movement of the knife when it has cut through the heel.

2. A heel-breasting machine comprising a shoe-support, a knife, power devices for actuating the knife positively or unyieldingly to breast the heel, and automatic mechanism for checking the movement of the knife relatively to the shoe without affecting the power devices.

3. A heel-breasting machine comprising a shoe-support, a knife, a knife-carrier, mechanism for imparting a positive or unyielding movement to the knife-carrier, and automatic devices for checking the movement of the knife-carrier relatively to the shoe.

4. A heel-breasting machine comprising a shoe-support, a knife, mechanism for moving the knife positively or unyieldingly, and an automatic device constructed and arranged to engage the sole of the shoe and check the movement of the knife relatively to the said shoe.

5. A heel-breasting machine comprising a shoe-support, a reciprocating driver, a knife, a knife-carrier actuated positively or unyieldingly by said driver, and mechanism for automatically throwing the said driver out of

operative relation with respect to the knife-carrier when the knife has cut through the heel.

6. A heel-breasting machine comprising a shoe-support, a knife, a knife-carrier, a driver for positively or unyieldingly actuating the knife, and a bunter arranged to slide relatively to said carrier and to disengage the carrier from the driver when the bunter engages the shoe.

7. A heel-breasting machine comprising a shoe-support, a knife, a knife-carrier, a toggle for operating the knife-carrier, and mechanism for automatically breaking said toggle when said knife has cut through the heel.

8. A heel-breasting machine, comprising a shoe-support, a reciprocating driver, a knife, a knife-carrier, a link connecting the knife-carrier and the said driver, and mechanism for automatically swinging the link and the driver at an angle to each other when the knife cuts through a heel.

9. A heel-breasting machine, comprising a shoe-support, a carrier, having a knife, a sole-engaging bunter having a guide, and a driver for actuating the knife-carrier and adapted to engage the guide, whereby when the bunter is held against movement by the shoe, the guide is engaged by the driver and the operative relation of the driver and the carrier is destroyed.

10. A heel-breasting machine, comprising a shoe-support, a carrier having a knife, an eccentric, an eccentric-rod, a link hinged to the eccentric-rod and to the carrier, and a bunter, constructed and arranged to engage a shoe and stop the travel of the knife-carrier relatively to the shoe by throwing the link and the eccentric-rod at an angle to each other.

11. A heel-breasting machine comprising power devices, a knife and its carrier positively actuated by said power devices, and a bunter arranged to stop the travel of the knife without affecting the power devices, said bunter including a finger with its end substantially parallel to the knife-edge, and adapted to engage the sole of a shoe.

12. A heel-breasting machine comprising power devices, a knife and its carrier positively actuated by said power devices, and a bunter arranged to stop the travel of the knife without affecting the power devices, said bunter including a finger with its end substantially parallel to the knife-edge, and adapted to engage the sole of a shoe, and means for adjusting the finger.

13. A heel-breasting machine including a shoe-support and a knife, of which elements one is movable relatively to the other, and a bunter yieldingly connected to the movable member and adapted to engage the sole of the shoe for the purpose of limiting the movement of the movable member.

14. A heel-breasting machine comprising a shoe-support, a movable knife, and mechanism for automatically driving said knife through a heel of any height to the sole, said

mechanism including a bunter for limiting the movement of the knife, said bunter being arranged to engage the sole with a pressure less than that with which the knife engages the heel.

15. A heel-breasting machine comprising power devices having a regular range of movement, a knife connected to said power devices, whereby it is positively actuated, and means for automatically varying the range of movement of the knife whereby it automatically breasts a heel of any height.

16. A heel-breasting machine comprising a knife, a shoe-support, means for operating the knife, a bunter yieldingly connected to the knife, and mechanism interposed between the bunter and the knife-operating means for automatically varying the movement of the knife whereby it breasts heels of varying heights.

17. A heel-breasting machine comprising a bed, having a table, a bearing-bracket at one end, and a bracket at the other end, all in substantially the same horizontal plane, a carrier and knife, mounted on said table, a shaft journaled in the first said bracket and connected to the knife-slide, and a jacking device mounted in the second said bracket, substantially as described.

18. A heel-breasting machine comprising a shoe-support, and a knife, in combination with mechanism to engage the corners and the tread of the heel and position it with respect to the knife.

19. A heel-breasting machine comprising a knife, means to engage and hold the shoe to the knife, and mechanism located between the said means and the knife for positioning the shoe with respect to the knife.

20. A heel-breasting machine comprising a knife, a support for the shoe, means for moving one of said parts relatively to the other, and mechanism for engaging the tread surfaces of the sole and heel, and adjusting them relatively to the knife and the support.

21. A heel-breasting machine, comprising a shoe-support, a knife mounted on one side of said support and movable in a plane transverse to the plane of the support, and mechanism on the other side of the support for jacking a shoe thereagainst, the said knife and said jacking mechanism moving in substantially the same or parallel planes.

22. A heel-breasting machine, comprising a bed, a knife and knife-carrier, a support pivoted to the bed, and means for jacking a shoe against the support.

23. A heel-breasting machine comprising a bed, a knife and its carrier, a shoe-support pivoted upon the bed and arranged to receive the tread-surface of the shoe, a link connected to the support on one side of its pivot, and means for fastening the free end of the link to the bed.

24. A heel-breasting machine comprising a knife, a support for the shoe, means for moving one of said parts relatively to the other,

and mechanism for engaging the corners of the top lift and positioning the heel with respect to the knife.

25. A heel-breasting machine comprising a shoe-support, a knife, and mechanism for automatically positioning the heel of a shoe relatively to the knife, irrespective of the size of the heel. 45

26. A heel-breasting machine, comprising a shoe-support, a knife, and automatic heel-positioning devices, movable toward and from each other, in a line parallel to the edge of the knife. 50

27. A heel-breasting machine comprising a shoe-support, a knife, devices for engaging the corners of the heel and positioning a shoe on said support with relation to the knife, and means for jacking the shoe against the support. 55

28. A heel-breasting machine comprising a shoe-support, a knife, and heel-positioning devices connected to move in unison but in opposite directions and mounted on said support. 60

29. A heel-breasting machine comprising a shoe-support, a knife, pivoted heel-positioning devices connected, to move in unison, and means for bodily moving said devices. 65

30. A heel-breasting machine, comprising a shoe-support, a knife, heel-positioning devices mounted upon said support to engage the corners of the heel, and means for adjusting said devices relatively to said knife. 70

31. A heel-breasting machine, comprising a knife, a shoe-support, centrally-pivoted positioning-fingers mounted on said support, means connecting said fingers to cause them to move in unison in opposite directions, and a curved guide to receive the upper ends of 40 said fingers. 75

32. A heel-breasting machine, comprising a shoe-support, devices on said support for positioning a heel, a knife and mechanism for moving said devices out of the path of the knife. 80

33. A heel-breasting machine comprising a knife and its carrier, a shoe-support, positioning devices on the support for a heel, and means actuated by the carrier for moving said devices out of the path of the knife. 85

34. A heel-breasting machine comprising a knife and its carrier, a shoe-support, positioning devices on the support for a heel, and means actuated by the carrier for moving said devices out of the path of the knife, said means including a pivoted lever, and a projection on the carrier to engage the lever. 90

35. A heel-breasting machine having a knife-blade at an angle to the tread-surface of the heel, and mechanism for engaging the sole and heel of a shoe and positioning it with respect to the knife. 95

36. A heel-breasting machine having a knife-blade with a cutting edge for breasting a heel, and mechanism for engaging the sole and heel and the edges of the top lift of the heel, and positioning the shoe with respect to the knife. 100

37. A heel-breasting machine comprising a knife, positioning gages or arms, and mechanism for adjusting said gages or arms in unison, whereby the operator can cut any desired quantity of stock from the top lift or heel. 105

In testimony whereof I affix my signature in presence of two witnesses.

JOHN J. HEYS.

Witnesses:

E. BATCHELDER,
A. D. HARRISON.
